UNITED STATES PATENT OFFICE.

EDWARD J. KILEY, OF CHICAGO, ILLINOIS, ASSIGNOR TO THE OHIO BRASS COMPANY, OF MANSFIELD, OHIO, A CORPORATION OF NEW JERSEY.

VALVE.

1,287,698.

Specification of Letters Patent.

Patented Dec. 17, 1918.

Application filed April 6, 1918. Serial No. 227,079.

To all whom it may concern:

Be it known that I, EDWARD J. KILEY, a citizen of the United States, residing at Chicago, in the county of Cook and State 5 of Illinois, have invented certain new and useful Improvements in Valves, of which the following is a specification.

This invention relates to valves, and more particularly to valves adapted for use in 10 connection with radiators for variably controlling the volume of fluid to be delivered at a predetermined opening of the valve, and has particular reference to the types of valves commonly known as "graduated" and 15 "packless" valves.

One object of this invention is to produce a valve of the character referred to, comprising improved means for effectively sealing the valve stem in all positions of the 20 valve.

Another object of my invention is to provide a graduated valve embodying improved means for variably controlling the amount of fluid delivered through the valve and an 25 indicating ring provided with improved means for adjustably interlocking the same with the casing.

A further object of the invention is to produce an improved valve which will be 30 simple, compact and durable in construction, and effective and efficient in operation.

To the attainment of the ends and the accomplishment of other new and useful objects as will appear, the invention consists in the features of novelty in the construction, combination and arrangement of the several parts hereinafter more fully described and claimed and shown in the accompanying drawings illustrating the embodiment of the invention, and in which:

Figure 1 is a central vertical sectional view of a valve embodying the principles of my invention.

Fig. 2 is a detail sectional view taken on the line 2—2 of Fig. 1.

Fig. 3 is a perspective view of a slotted washer which is employed in the construction disclosed.

Fig. 4 is a sectional view taken on the line 4—4 of Fig. 1.

Similar reference characters denote corresponding parts in the various views.

The valve herein disclosed comprises a body 1, provided with an inlet and outlet 2 and 3, respectively, which may be threaded

as shown for connection with a radiator or the like. The upper end 4, of the body is apertured and internally threaded for the reception of the externally threaded sleeve 5, of the bonnet 6, which is provided with a shoulder 7, adapted to seat against the end surface of the body to prevent leakage. For the purpose of controlling or governing the amount of fluid to be delivered through the device, a valve member 8, having a threaded connection with the valve stem 9, is provided. The valve member 8 is preferably constructed as shown and is mounted for longitudinal movement relatively to the stem, but interlocked against rotation relatively to the body 1 by means of projections 10 provided on the inner surface of the sleeve 5, and grooves 11, formed in the periphery of the upper portion of the valve member 8, which is slidably mounted in the opening 12 of the sleeve 5. The lower portion 8¹ of the valve member 8 is shown as substantially conoidal in shape, and is adapted to coöperate with the port 13 formed in a web in the casing 1, to variably control the amount of fluid delivered through the device, the greatest diameter of the portion 8¹ being substantially the same as the diameter of the port. Disposed below and in alignment with the port 13 is a second port 14 formed in a web in the casing, which is of smaller dimensions than the first mentioned port and is provided with a flaring seat 15, adapted to be engaged by the exterior surface of the portion 8¹ adjacent its small end to prevent passage of fluid through the device. It will be obvious that by rotation of the stem 9 in one direction the valve member 8 may be moved into engagement with the seat 15 to close the valve to prevent passage of fluid therethrough as shown in Fig. 1, and that by rotation of the stem in the opposite direction the valve member will move out of engagement with the seat 15, thereby opening the valve to permit fluid to be delivered therethrough. The amount of fluid delivered through the device is governed by the lift or the amount of movement imparted to said valve member, the conoidal portion 8¹ thereof coöoperating with the port 13, to vary the effective opening of said port in a manner as will be readily understood. It will be obvious from the foregoing that one size of valve constructed as herein described and illustrated

in the drawings may be employed to properly control the fluid supply to radiators irrespective of their size and capacity.

The valve stem 9 is rotatably mounted in a suitable aperture formed in the bonnet 6, and is provided with a flange 16 having an annular arcuate bearing surface adapted to seat against the inner surface of the flanged cone shape sealing member 17, which is mounted in a counterbore of similar conformation formed in the bonnet. The sealing member is preferably composed of metal having softer characteristics than the flange 16; such for instance as lead, tin, zinc, copper, etc., or a metallic alloy thereof, and may be secured into the counterbore by compression or by a peening operation to secure a joint that will be proof against leakage. While I have shown the member 17 as being secured in the valve casing, it will be obvious that it may be mounted on the valve stem if desired, and adapted to coöperate with a bearing surface provided in the casing. Positioned within the cavity 18 formed in the bonnet 6, and surrounding the stem 9, is a compression spring 19, which exerts a pressure against the U shape washer 20 which is removably mounted in an annular groove 21, formed in the stem 9. This spring constantly urges the valve stem 9 in an upward direction and tends to yieldingly maintain the flange 16 in contactual engagement with the sealing member 17, thereby effecting a perfect seal between the two, as readily will be understood. Adjustably mounted upon the shoulder 22, formed on the exterior surface of the bonnet 6, is an indicating ring 23 upon which in turn rests a retaining disk 24. The indicating ring 23 is formed with a serrated opening adapted to the casing so as to engage the angular portion thereof to adjustably retain said ring in any desirable position, as shown in Fig. 4, and has a stop lug 23¹, preferably formed integral therewith, for a purpose to be described hereinafter. The bonnet 6 is also provided with a reduced extension or neck 25 which projects through a suitable aperture provided in the retaining disk 24 and is adapted to be received within the opening 26 of the cap 27, which is mounted upon said retaining disk. The cap 27 is provided with a handle 28, and has a polygonal opening adapted to slidably receive the end 30, of the stem 55 which is of similar conformation, whereby a rotation of the cap will impart movement to said stem. A screw 31, engaging the end of the stem and having its head disposed in a counterbore formed in the top of the cap 60 may be employed for securing the latter in position, and a lock washer 32, may be provided for preventing the screw from working loose. The end 30 of the stem is shown as mounted in the cap in a manner to permit axial movement of the stem 9, relatively.

to said cap as the parts become worn by use when in service. This arrangement eliminates the possibility of breaking the seal around the stem and consequent leakage as the result of downward pressure on the operating handle or on the end of the device, which is an objectionable feature common to devices of this character. Formed integral with the cap on one side thereof is an indicator 33, which is adapted to engage and coöperate with the lug 23¹, to determine the full open position of the valve, while other positions of the valve may be represented by marks, as shown or otherwise.

The cap 27 may be provided with a cover 80 34, which can be readily removed when it is desired to readjust the screw 31 to compensate for wear of the parts.

Having fully described my invention and shown one form embodying the same, I do not wish to be limited to the details of the construction shown, since these can be obviously changed without departing from the spirit and scope of the invention.

What I claim as new and desire to secure by Letters Patent is:

1. A valve comprising a casing provided with a seat, a valve member for the seat, a rotary valve stem provided with an arcuate bearing surface and having a threaded connection with the valve member, a sealing member secured in a recess in the casing having a surface adapted to coöperate with said arcuate bearing surface to effect a packless seal; a U shape washer removably mounted in a groove in the stem for taking the end thrust of a spring, a spring exerting its tension on said washer to maintain said coöperating surfaces in sealed position, and means for operating the valve.

2. A valve comprising a casing provided with a seat and a cavity, a valve member movable in and out of engagement with the seat, but interlocked with the casing against rotation, a rotary valve stem threadedly connected with said valve member and provided with an annular arcuate bearing surface, a metallic sealing member secured in a recess in the casing, said sealing member having a conical surface adapted to coöperate with the arcuate bearing surface of the stem to effect a seal to prevent leakage between the two; a U shape washer mounted in a groove in the stem, a spring in the cavity exerting its tension on said washer for constantly maintaining the coöperating surfaces in sealed relation; a cap engaging the stem to rotate the same, a pointer on the cap, a handle for the cap, and an indicating ring adjustably mounted below said cap and retained in place thereby.

3. A valve comprising a casing, a plurality of aligned and spaced ports therein, a closure member in telescopic relation with one of said ports and mounted for vertical movement

and shaped so as to vary the effective opening thereof and having a surface adapted to cooperate with a seat surrounding the other port to close the valve, a rotary valve stem 5 movably supporting the closure member, a metallic sealing member fixed in the casing, coöperating surfaces between the stem and the sealing member to effect a packless seal, means yieldably maintaining said coöperating 10 surfaces in sealed relation, and means for operating the valve.

4. A valve comprising a casing provided with a web having a cylindrical port formed therein, a closure member in telescopic relation with said port and movable relatively thereto and shaped so as to vary the effective opening thereof, a rotatable valve stem movably supporting the closure member, and a second port in alignment with and of 15 smaller dimensions than the first mentioned port and provided with a seat adapted to coöperate with said closure member to prevent the passage of fluid through the valve, in combination with a sealing member having 20 a surface coöoperating with a surface of the stem to prevent leakage around the latter, and means for operating the valve.

5. A valve comprising a casing having two ports formed therein, a vertically movable closure member adapted to coöperate with one of said ports and shaped so as to variably control the amount of fluid delivered through the valve and movable into engagement with a seat encircling the other 30 port to close the valve, a rotatable stem movably supporting said closure member, a sealing member around the stem, a cap slidably engaging the stem to rotate the same, said cap being free to move axially relatively 35 to said stem without breaking the seal.

6. A valve comprising a casing, a web having a valve seat therein, a valve member for the seat, a rotary stem for operating the valve member, a web having a port formed 40 therein and coöperating with the valve member, the valve member so shaped to variably control the amount of fluid delivered

through the valve, a sealing member around the stem, a cap slidably engaging the stem to rotate the same, adjustable means engaging 50 the end of the stem for retaining said cap in position, a handle for the cap, and an indicating ring adjustably mounted below said cap and retained in place thereby.

7. A valve comprising a casing, a plurality of vertically aligned and spaced ports therein, a common closure member movable within one of the ports to vary the effective opening thereof and movable into engagement with a seat encircling another port to 55 close the valve, a rotary valve stem supporting the closure member, a sealing member around the stem, coöperating surfaces between said sealing member and stem to effect a packless seal, means tending to yieldably maintain the coöperating surfaces in 60 sealed relation, a cap provided with a handle slidably engaging the stem to rotate the same, and an indicating ring provided with a serrated opening for engagement with the 65 casing adjustably mounted below the cap.

8. A valve comprising in combination a casing provided with a seat therein, a valve member for coöperating with the seat, a grooved valve stem co-acting with the valve 70 member to move the same relatively to the seat, an annular bearing member projecting from the stem, a sealing member coöperating with the annular bearing member to effect a seal to prevent leakage around the 75 stem, a slotted washer mounted in the groove in the stem, a cavity surrounding the groove in the stem, a spring in the cavity pressing against the washer to maintain a sealed relation between the coöperating surfaces of 80 said annular bearing and sealing members, a tap carrying an indicator engaging the stem to rotate the stem, a handle on the tap and a ring having means for coöperating 85 with said indicator for indicating the amount of angular movement of the stem.

In testimony whereof I affix my signature.

EDWARD J. KILEY.
